(57) **CLAIM**

The ornamental design for a reader for mobile device, as shown and described.

DESCRIPTION

FIG. 1 is a perspective top view showing our new reader design for a mobile device;

FIG. 2 is a perspective bottom view thereof;

FIG. 3 is a front view thereof;

FIG. 4 is a side view thereof;

FIG. 5 is another side view thereof;

FIG. 6 is a back view thereof;

FIG. 7 is a top view thereof; and,

FIG. 8 is a bottom view thereof.

In the drawings, the broken lines depict environmental subject matter only and form no part of the claimed design.
